UNITED STATES PATENT OFFICE.

WILLIAM J. MURPHY AND ALBERT E. CULLEY, OF BUTTE, MONTANA.

CONVERTER.

972,564.

Specification of Letters Patent.

Patented Oct. 11, 1910.

Application filed April 23, 1910. Serial No. 557,250.

To all whom it may concern:

Be it known that we, WILLIAM J. MURPHY and ALBERT E. CULLEY, both citizens of the United States, residing in Butte, county of 5 Silverbow, and State of Montana, have invented certain new and useful Improvements in Converters, of which the following is a specification.

This invention relates to converters and 10 particularly to converters of that type in which the molten charge is converted by blowing a blast of air therethrough.

Converters as now used are generally provided with a refractory lining and it is 15 found in practice that the charge will rapidly attack this lining so that it must be renewed after a comparatively small number of charges have been operated upon. This is especially true where sulfid ores of 20 copper are worked upon, since it is necessary that some fluxing material be provided so that the impurities in the ore may combine with the flux to form a fusible slag. In such cases the impurities in the charge will 25 combine with the lining to form the slag.

The objects of this invention are therefore to so construct and operate a converter that its lining will be protected against the destructive action of the charge.

30 The invention will be described in connection with the accompanying drawings in which,

Figure 1. is a front elevation showing an apparatus for carrying on this invention. 35 Fig. 2. is a section on line 2—2 Fig. 1, parts being shown in elevation, Fig. 3. is a longitudinal vertical section, and Fig. 4. is a section on line 4—4 Fig. 3.

The converter comprises a cylindrical 40 shell 10 lined with a suitable refractory lining and mounted for tilting movement on rollers 11. The converter is tilted in the usual manner by means of a motor 12 provided with a rack 13 engaging a pinion 14 45 on the cylinder. The air is supplied from a supply pipe 15 to the wind box 16 and from there distributed to the twyers 17. The construction so far described is well known.

The converter is provided with removable 50 cap 18 which is bolted thereon and a throat or stack 19 is located at one end of the cap. The cap like the body is provided with a refractory lining and the converter is further provided with a tap hole 20 and a spout so 55 that the charge may be tapped. It will be understood that during the converting oper-

ation the tap hole will be closed by means of a suitable plug.

The walls of the converter are provided with conduits or passages 21 which extend 60 through the walls and into the interior. These conduits or passages are preferably located at the ends and incline downwardly as shown, and are provided with filling hoppers 22. The inner wall of the converter 65 has formed thereon a rib 23, and the wall extends rearwardly from the rib toward the ends; these ends are preferably rounded as shown for a purpose hereinafter to be described. 70

A fluxing material in a divided or granular condition is supplied to the hoppers 22 and introduced into the converter, and this fluxing material is spread on the bottom and banked against the walls as shown in Fig. 3. 75 The charge is now introduced and the blast turned on. During this operation the charge will feed upon fluxing material in preference to feeding upon the lining of the converter. The hoppers are constantly kept 80 filled so that an excess of fluxing material is constantly present and this material will be introduced into the converter against the end walls so as to form a protective lining as shown in Fig. 3. The banking of the 85 fluxing material against the walls is facilitated due to the fact that conduits 22 incline downwardly. The blast will cause the charge to be blown against the wall opposite that which the twyers are located, and 90 the molten charge will strike the rib 23 and will be divided and directed and deflected against the fluxing material at the end walls. The charge will thus be given a movement 95 against the fluxing material so as to thoroughly come in contact with the same, and the rounded construction of the ends will cause the metal to be given a rotative movement right and left thereby further facilitating the operation. It will thus be seen 100 that this invention provides means whereby the converter will be made self-lining. The character of the fluxing material will depend upon the character of the ore worked upon. For copper ores containing iron and sulfids a silica flux will be used. In all cases however, the flux is introduced into 105 the converter so that the charge will act upon it in preference to the lining. This invention thereby provides means whereby a converter may be used for a large number of charges without necessitating relining.

The fluxing material may be introduced directly into hoppers 22 with shovels or in any other suitable manner. In order that this material may be conveniently introduced a pair of supply hoppers 24 are mounted upon a frame 25 and pipes 26 extend from these hoppers over the hoppers 22. Each of the hoppers 24 is provided with a feed slide 27, operated by a handle 28. 10 This provides a very convenient arrangement for introducing fluxing material and also permits free movement of the converter.

It will be noted that the converter is 15 cylindrical in section throughout its entire length as distinguished from converters now in use in which the interior tapers from the bottom to the centrally located throat. The removable cap 18 permits easy inspection 20 of the converter and also facilitates relining when necessary. By placing the stack 19 at the end of the converter and by making the interior cylindrical, splashing of the metal is prevented, thus minimizing the 25 danger to the operator.

It is obvious that various changes may be made in the details of the apparatus without departing from the spirit of this invention, and it is therefore to be understood that this 30 invention is not to be limited to the specific arrangements shown and described.

Having thus described the invention, what is claimed is:

1. The combination in a converter having 35 walls, of flux conduits extending into said converter, and constructed to introduce a fluxing material into the converter and to deliver the same against said walls to form a protective lining therefor.

40 2. The combination in a converter having walls, of means for introducing a fluxing material into the converter and for delivering the same against said walls to form a protective lining therefor, and means for 45 directing the charge against the fluxing material so introduced.

3. The combination in a converter having walls, of means whereby a fluxing material may be introduced into the converter and 50 against said walls, and means for directing the charge against that portion of the wall which is covered by the fluxing material.

4. The combination in a converter having 55 walls, and twyers for introducing a blast to agitate the charge, of means whereby a fluxing material may be introduced into the converter and deposited against some of said walls, and a deflecting rib on one of said walls constructed to direct the agitated 60 charge against the fluxing material.

5. The combination in a converter having 65 twyers and walls shaped to provide a forwardly projecting portion opposite said twyers, the portion on each side of the rib curving rearwardly toward the ends.

6. The combination in a converter having walls and twyers therein for introducing a blast into the converter to agitate the charge therein, of deflecting means on said walls constructed to coöperate with the blast to 70 impart a movement to the charge from the center toward the ends of the converter.

7. The combination in a converter having walls and twyers therein for introducing a blast into the converter to agitate the charge 75 therein, of means for introducing a fluxing material into the converter and against the end walls, and deflecting means on said walls constructed to coöperate with the blast to 80 impart a movement to the charge from the center toward the charge against the end walls.

8. The combination in a converter having twyers and walls shaped to provide a forwardly projecting rib opposite said twyers, the portion on each side of the rib curving rearwardly toward the ends, and the 85 ends being rounded.

9. In a converter, the combination with a 90 movable member thereof, of a support therefor, and a flux conduit extending through the wall of the movable member and movable therewith, said conduit being constructed to introduce a fluxing material into said converter and against the wall. 95

10. The combination in a converter having 100 walls, of downwardly inclined conduits extending through said walls and constructed to introduce a fluxing material into the converter and against the walls.

11. In a converter, the combination with a 105 movable member thereof, of a support therefor, a flux conduit extending through the wall of the movable member and movable therewith, and a fluxing material supply having a discharge coöperating with said 110 conduit for introducing said material into said converter, said conduit being constructed to deliver the fluxing material against said wall to form a protective lining. 110

12. In a converter, the combination with a 115 movable member thereof, of a support therefor, a flux conduit extending through the wall of the movable member and movable therewith and provided with a hopper, a supply for fluxing material above the converter, and a discharge pipe from said supply arranged to introduce fluxing material into 120 said hopper through said conduit into the converter, said conduit being constructed to deliver the fluxing material against said wall to form a protective lining.

In testimony whereof, we have hereunto subscribed our names.

WILLIAM J. MURPHY.
ALBERT E. CULLEY.
